UNITED STATES PATENT OFFICE.

EDMOND C. SMITH, OF SAUGATUCK, AND CYRUS L. MEADE, JR., OF WESTPORT, CONNECTICUT, ASSIGNEES TO THE SANITARY COUPLING COMPANY, OF SAUGATUCK, CONNECTICUT, A CORPORATION OF DELAWARE.

WATER-CLOSET COUPLING.

SPECIFICATION forming part of Letters Patent No. 712,012, dated October 28, 1902.

Application filed May 22, 1902. Serial No. 108,503. (No model.)

To all whom it may concern:

Be it known that we, EDMOND C. SMITH, residing at Saugatuck, and CYRUS L. MEADE, Jr., residing at Westport, county of Fairfield, 5 State of Connecticut, citizens of the United States, have invented a new and useful Water-Closet Coupling, (Case A,) of which the following is a specification.

This invention relates to certain improvements in couplings for water-closets, and has for its object to provide a coupling between a soil-pipe and a ceramic bowl which shall be thoroughly sanitary, as the escape of sewer-gas is made impossible, of few parts, which are 15 relatively inexpensive and easily put together and thoroughly durable, as the bowl is not attached to the floor, but to a metal base, so that all difficulty in setting up and danger of breakage owing to unevenness of floors and 20 their swelling, shrinkage, or settling is avoided.

It is an essential feature of this invention that we produce a water-closet coupling in which the soil-pipe is secured to and suspended from a metal base and without connection 25 either with the floor or the bowl.

With the above and other objects in view the invention consists in certain constructions and in certain parts, improvements, and combinations which will be hereinafter described 30 and then specifically pointed out in the claims hereunto appended.

In the accompanying drawing, forming part 35 of this specification, in which like characters of reference indicate the same parts, the figure is a sectional view illustrating the mode in which we have carried the principle of our invention into effect.

A denotes a ceramic water-closet bowl having a flange 10; B, a metal base having an upper flange 11 corresponding with flange 10 upon the bowl, and a lower flange 12, which rests upon the floor C; D, a two-part clamp adapted to engage flanges 10 and 11 and se- 45 cure the bowl to the base, and E is a soil-pipe whose upper end is flanged over, as at 13, as a means of rigidly securing it to the base.

The base B is made in two parts, which are denoted, respectively, by 18 and 19. The

lower part (indicated by 19) is provided with 50 an internal shoulder 20 and above said shoulder with a female thread 21, and the upper part (indicated by 18) is provided with a depending collar 22, having a male thread corresponding with the female thread on part 19. 55 As the bowl is not attached to the base until after the latter is in position, it is obvious that the lower end of the collar may be turned down upon the flange of the soil-pipe just as tightly as may be required to insure a perfectly tight joint. Then the bowl is set upon the base, packing 15 being interposed, and said parts are secured together by a clamp D.

In setting up a water-closet where our novel coupling is used the soil-pipe is passed up 60 through the floor, the metal base placed over the soil-pipe and secured in place, then the upper end of the soil-pipe is flanged over either upon an internal shoulder on the base or over the top of the base, so as to secure it 70 thereto, and then the bowl is placed in position on the base and secured there by a two-part clamp engaging flanges on the base and bowl, respectively, as clearly shown in the drawing, packing, as a gasket, being always 75 used between the bowl and the base.

We do not claim herein a closet-coupling comprising a soil-pipe having a flange for securing it in place, a metal base for attachment to the floor and having a recess to receive the 80 flange, and a ceramic bowl resting upon and secured to the base and having its weight supported thereby, as the same forms the subject-matter of our application Serial No. 108,504, filed concurrently herewith. 85

Having thus described our invention, we claim—

1. In a coupling of the character described, the combination of a metal base formed of two interlocking members having an annular 90 space between them, of a soil-pipe having a flange fitting in said space and engaged by said interlocking members, and a bowl supported by said base.

2. In a coupling of the character described, 95 the combination of a metal base formed of two interlocking members, one of which is provided with an internal shoulder, of a soil-

pipe having a flange resting on said shoulder and interposed between meeting faces of said locking members, and a bowl supported by said base.

5 3. In a coupling of the character described, the combination of a lower member having an internal shoulder, an upper clamping member, a soil-pipe having a flange resting on said shoulder and engaged by said clamping member, and a bowl supported by said clamping member.

4. In a coupling of the character described the combination with a metal base consisting of a part 19 adapted for attachment to a floor 15 and having an internal shoulder and a female

thread and a part 18 having a depending collar threaded to engage the other part, of a soil-pipe flanged externally to secure it to the shoulder and gripped between said shoulder and collar, a bowl resting upon the base, and a clamp by which the bowl is secured to the base. 20

In testimony whereof we affix our signatures in presence of two witnesses.

EDMOND C. SMITH.
CYRUS L. MEADE, JR.
